AUTOMOBILE LIGHTING AND SIGNAL SYSTEM

Julius C. Ford, Memphis, Tenn.

Application May 6, 1935, Serial No. 19,968

2 Claims. (Cl. 200—59)

This invention relates to improvements in automobile lighting and signaling systems, but particularly to the switch control mechanism by means of which the operation of the direction indicating signals is accomplished.

The primary object of this invention is to provide a switch for attachment to a pedal of an automobile, which switch will reliably accomplish at option the operation of the direction control and other lights, and which switch will not interfere with the independent operation of the pedal itself.

The means by which these and other objects are accomplished, and the manner of their accomplishment will be readily understood from the following description on reference to the accompanying drawing, in which,—

Fig. 1 is a side elevation showing the casing of the direction control switch mounted on a foot pedal.

Fig. 2 is a view of the switch looking in the direction of the arrow 2 of Fig. 1.

Fig. 3 is a sectional view of the switch taken on the line III—III of Fig. 1.

Fig. 4 is a sectional view taken as on the line IV—IV of Fig. 3.

Fig. 5 is a fragmentary sectional plan taken as on the line V—V of Fig. 3.

Fig. 6 is a sectional plan taken on the line VI—VI of Fig. 3; and

Fig. 7 is a diagrammatic view showing the wiring system of the lights and the controls therefor.

Referring now to the drawing in which the various parts are indicated by numerals, 12 is one of the foot pedals of the automobile to which is secured a directional-signal control-switch 13. 25—25 are right and left hand head-light bulbs and 29—29 an additional pair of headlight bulbs 30 similarly right and left. 30L and 30R are respectively right and left hand signal bulbs at the front of the car and 47L and 47R corresponding signal bulbs at the rear of the car. 49 is a tail light.

45 The directional control switch 13 comprises a casing 60, which is secured to the foot pedal 12 and its shank 61, as by screws 62 and a clamp 63. Mounted within the casing 60 are metal strips 64, 65 each secured as by bolts 66 to a member 67 50 of insulating material such as "bakelite". These strips carry contact points 68L, 68R. From the contact point 68L, a wire 43L connects to the front directional signal bulb 30L and a connected wire 50L to the rear directional signal bulb 47L, 55 and from the contact point 68R a wire 43R con-

ncts to the front directional signal bulb 30R and a connected wire 50R to the rear directional signal bulb 47R.

Also mounted within the casing 60 is a metal strip 70 secured as by a bolt 71 to the insulating member 67 which strip carries contacts 72L, 72R and a third strip 73 similarly secured to the insulating member and carrying contacts 74R and 74L. The contacts 72L and 72R are jointly connected by a wire 75 to a battery 76 or other source of current. From this battery also a wire 77 leads to a hand operated switch 44. The wire 51 from the tail light 40 leads to both of the contacts 74R and 74L. Depressibly mounted in the casing 60 as on a horizontally disposed bolt 80 are arms 81L, 81R, which are resiliently supported as by a spring 82. Portions 83L, 83R of the arms 81L, 81R respectively extend upward through the top of the casing 60 and are jointly secured to a transverse pressure bar 84 as by screws 85. Secured to the arm 81L but insulated therefrom as by insulation 86 is a contact bar 87L which lies above all three of the contacts 68L, 72L and 74L, and a similar bar 87R is similarly carried by the arm 81R.

The manual switch 44 has three contacts 90, 91 and 92 a wire 52 from the tail light 49 leading to the first of these contacts. Circuit wires 93 lead from the contact 91 to the head light bulbs 25 and circuit wires 94 from the contact 92 to the headlight bulbs 29. 95 is a manually movable contact bar connected through the wire 77 to the battery 76 and adapted to contact with each of the contact points 90, 91 and 92 in succession. An extension 96 of the bar permits contact to be maintained with all three of the contacts 90, 91 and 92 as the bar is progressively moved forward.

In using the device the contact bar may be shifted into engagement with the contact 90 to put on the tail light 49 as for parking. The bar may further be shifted into engagement with the contact 91 to turn on the head lights 25 while maintaining contact with the tail light or it may further be shifted to bring in the headlights 29 in addition.

The use of the directional signal is not dependent on the use of the head light system and irrespective of whether such head lights and tail lights are turned on may be used. To use the 50 directional signal, with the foot on the pedal 12 the left end of the bar 84, or the right end of the bar 84, as may be desired, is depressed by the forward portion of the foot, dependent on whether a turn is to be made to the left or the right. De- 55

pression of the left hand side depresses the contact bar **87L** into engagement with the contacts **68L**, **72L** and **74L** closing the circuit from the battery **16** to the front signal bulb **30L** through the circuits **43L**, **50L** and to the tail light **49** through the circuit **51**. Similar action for the right signal lights and the tail light is accomplished by pressure on the right end of the bar **84**.

Should it be desired to indicate a stop, the entire bar **84** is depressed and all four signal lights as well as the tail lights are turned on.

What I claim is:

1. A switch for an automobile having a foot pedal, said switch including an enclosing casing rigidly attached to said pedal, and having a top forming a foot-contacting portion relatively immovable with regard to said pedal; said casing enclosing, a base of insulating material, two oppositely disposed banks of contacts supported and insulated by said base, a shaft supported by said casing above said base and between said banks of contacts, a pair of arms independently hinged on said shaft and extending oppositely outward, a pair of bus bars, each carried by a said arm and overlying a said bank of contacts, spring means supporting said arms to hold said bus bars free from said contacts; posts, respectively projecting each from a said arm through and above

said top, and a bar external to said casing having its opposite ends secured each to a said post, said bar being compressible relative to said casing to optionally engage either or both of said bus bars with its or their respective contacts.

2. In directional signal actuating means for an automobile, having directional signal devices, and a foot pedal, which includes a shank and a foot portion carried thereby, control means including a housing having an integral rearwardly projecting plate and rearwardly projecting clamping means spaced from said plate, the surface of said plate forming a rearward continuation of the surface of said housing and said plate being adapted to rigidly overlie said pedal foot-portion, said clamping means being adapted to engage and be rigidly secured to said pedal shank, said housing being thereby rigidly supported forwardly of said pedal, said housing enclosing signal-actuating contact-means and having adjacent its forward edge a resiliently supported bar spaced above the top of said housing and operably connected through said top with said contact means, said plate forming a support whereby to permit an autoist's foot to rest on said pedal without actuation of said signals.

JULIUS C. FORD.
